UNITED STATES PATENT OFFICE.

NICHOLAS HAYDEN AND CHARLES F. C. WURST, OF ST. PAUL, MINNESOTA.

DESIGN FOR A WHIFFLETREE-HOOK.

SPECIFICATION forming part of Design No. 25,548, dated May 26, 1896.

Application filed April 17, 1896. Serial No. 588,046. Term of patent 14 years.

To all whom it may concern:

Be it known that we, NICHOLAS HAYDEN and CHARLES F. C. WURST, citizens of the United States, residing at St. Paul, in the 5 county of Ramsey and State of Minnesota, have invented a certain new and useful Design for Whiffletree-Hooks; and we do declare the following to be a full, clear, and exact description of the invention, such as will enable others skilled in the art to which it 10 pertains to make and use the same, reference being had to the accompanying drawing, which forms a part of this specification.

This invention relates to a certain new and 15 useful design for hooks of the character adapted for use as whiffletree-hooks.

The invention is clearly illustrated in the accompanying drawing, which forms a part of this specification, and in which we have 20 shown a perspective view of a hook embodying our design.

The essential feature of our design resides in the body portion of the hook, which is constructed to represent the breast and curved neck and head of a swan, the general outline 25 of the hook in side elevation being that of the letter **S** reversed, with the lower loop somewhat enlarged.

Having thus described our invention, what we claim to be new, and desire to secure by 30 Letters Patent, is—

The design for a hook, substantially as shown and described.

In testimony whereof we affix our signatures in presence of two witnesses.

NICHOLAS HAYDEN,
CHARLES F. C. WURST.
